[57] ABSTRACT

Shower apparatus has a pressure fluid conduit with spray nozzles having body portions immersed in the fluid and internal valve members movable between a spray position restricting the capacity of the spray outlet and a purge position in which such capacity is enlarged, the nozzle body portions having inlet and outlet ports differently located in the fluid flow path in the manifold so that the valve members are shifted between spray and purge positions by pressure differential changes between the pots produced by opening and closing a conduit outlet valve to vary the fluid flow rate.

5 Claims, 4 Drawing Figures

SPRAY APPARATUS

This invention relates to spray apparatus and particularly to self-cleaning spray apparatus of the type disclosed in my U.S. Pat. Nos. 3,073,529 and 3,249,305, issued Jan. 15, 1963 and May 3, 1966, respectively.

In apparatus of the type concerned, spray nozzles are provided with valve members which are movable between a spray position in which they restrict the spray outlet and a purge position in which they are retracted from and no longer restrict the spray outlet, so that foreign matter that may have collected in the nozzle can be flushed out of the enlarged outlet. Movement of the valve members between the two positions has been produced by changing the relative fluid pressure conditions in the two conduits to which ports in the nozzle body are respectively exposed.

Such spray apparatus has important advantages over other types and has had substantial usage in applications where the spray fluid contains solid materials which are likely to plug the spray outlets. However, it is relatively expensive to fabricate, in part because of the requirement of two conduits into both of which the nozzles extend. This requirement has been met by providing an intermediate dividing wall in a single pipe, thus dividing the pipe into two conduits having separate flow control valves. The nozzle bodies are fastened in fluid tight relation through aligned apertures in the pipe and dividing wall. Such structure is difficult to make, particularly in cases where the pipe must be curved or bent.

The object of the invention is to provide improved apparatus of this type which operates by changing flow conditions in only a single conduit to which the nozzle bodies are exposed, thus eliminating the difficult and expensive fabricating operations of the two conduit apparatus of the prior art.

It has now been discovered that if fluid flow in a single conduit is altered between relatively slow, corresponding to spray condition of the nozzles, and relatively fast, corresponding to their purge condition, pressure conditions about the bodies of spray nozzles projecting across the flow change from substantially uniform for the slow flow to differential pressure on different parts of the nozzle body for the fast flow. Utilizing this discovery, the invention provides a single conduit in which such different fluid flow conditions may be alternately produced, and nozzle bodies having an inlet port located in an area subjected to relatively high pressure at fast flow and an outlet port located in an area subjected to relatively low pressure at such flow, the inlet port being located between the outlet port and the spray outlet. Under slow flow, there is a pressure differential between the two ports in the direction to move the valve members into the spray position and hold them there. However, under fast flow, the pressure differential reverses direction which moves the valve members into purge position.

In preferred embodiments, the inlet port is located in the upstream face of each nozzle body while the outlet port is located either in the opposite downstream face or the bottom thereof, the upstream face being a relatively high pressure area to the other two port locations under fast flow. The conduit is provided with a discharge valve at the end opposite the inlet which is closed or substantially so for spray and opened for purge, the capacity of the conduit and valve being such

that the flow rate through the conduit when the valve is open is much greater, preferably several times greater, than the flow rate when the valve is closed. The valve members are most desirably of the type which have an enlargement located between the inlet and output ports.

The foregoing and other objects, features and advantages of the invention will be more fully understood from the ensuing particular description and the accompanying drawing wherein:

FIG. 1 shows apparatus according to the invention partially broken away, the conduit and discharge valve being shown in longitudinal section and the nozzles in side elevation;

FIG. 2 is a view partly in section, partly in elevation of a nozzle of FIG. 1, taken on line 2-2 of FIG. 1 in the direction of the arrows;

FIG. 3 is a cross-section view on line 3-3 of FIG. 2, showing the valve member in purge position; and

FIG. 4 is a cross-sectional view of another form of nozzle.

Referring to FIG. 1, the apparatus has a single conduit manifold 10 having a threaded inlet end 12 for receiving a coupling connection to a source (not shown) of spray fluid (e.g., white water in paper mill use) under pressure. The opposite end of the manifold has an outlet extension 14 which may, for example, be connected to a recirculation system and is controlled by a valve 16 shown in the open (purge) position, valve 16 having its port 18 substantially of the same cross-sectional size as manifold 10. Manifold 10 has mounted therein a plurality of nozzle bodies 20 which extend through apertures in the wall of the manifold and are secured thereto adjacent the spray outlet ends 22 thereof by welding as shown, or by screw threading, so that the outlet ends 22 project outwardly of the manifold.

As shown in FIGS. 1-3, nozzle bodies 20 are generally cylindrical members having an interior chamber 24 in which a valve member 26 is axially movable. The nozzle bodies are provided with an inlet port shown as a slot 28 which faces upstream in the manifold and an outlet port shown as a slot 30 in the opposite side facing downstream, the inlet slot being closer to the spray outlet end 22 than the outlet slot. As shown, the outlet end are formed of plugs having shanks 32 which fit inside the outer end of the nozzle bodies and have a projecting flange 33 which seats against the outer end of the valve body. An O-ring (not shown) may be provided in a groove in the outer end of the valve body to insure a tight seal with flange 33. The plugs have an interior passage 34 which forms a continuation of chamber 24, and a spray port 36, shown as a slot of roughly V-shaped cross-section, opening from passage 34 through the sidewall of the plug. The ends of bodies 20 opposite spray ends 22 are closed beyond outlet slot 30. A nut 37 is fastened over the screw threaded exterior end of body 20 to retain the plug in place.

Valve members 26 are in the form of pistons having an enlarged base end 38 and a hollow shank 40 open at its end opposite base 38 and provided with an inlet port shown as a slot 42 through the wall thereof adjacent base 38. The open end of shank 40 has a substantially spherically shaped enlargement 44 which seats against the upper end of passage 34 in the spray position shown in FIG. 2 so as to restrict but not entirely close spray slot 36.

In operation, with valve 16 closed, valve members 26 are in the spray position shown in FIG. 2. The spray fluid flows into the inlet slots 28 in nozzle bodies 20 and the inlet ports 42 of their valve members 26, thence out the restricted portion of slot 36 beyond the open end of the valve members to form the spray, as indicated by the dashed arrowed line in FIG. 2. With valve 16 closed fluid discharge from manifold 10 is relatively small, the flow therein is relatively slow and pressure conditions in the fluid surrounding the inlet and outlet ports are similar. The flow through inlet port 28 to the spray outlet creates a pressure differential on the opposite side of base 38 which maintains the valve members in the spray position of FIG. 2.

At purge, valve 16 is opened to the position of FIG. 1 causing relatively large discharge from conduit 10 and relatively fast flow of fluid therein. The pressure on the upstream face of the nozzle bodies becomes greater than on the downstream face, creating a pressure differential in the nozzle bodies toward their outlet ports 30 which forces the valve members toward the outlet ports to their purge position of FIG. 3. Fluid flows from inlets 28 directly to and out the now unrestricted spray outlets 36 as well as through inlet ports 42 and the valve bodies as indicated by the dashed arrowed lines in FIG. 3, carrying with it foreign matter which accumulated in the nozzle bodies since the previous purge because it was too coarse to pass through the spray outlets 36 restricted by the valve members in spray position. On closing valve 16, the original pressure differential is restored, returning the valve members to the spray position of FIG. 2.

Thus, the valve members loosely, freely movable in the nozzle portions are shifted from spray to purge back to spray positions simply by opening and closing an exhaust valve in a single conduit manifold. In order to insure satisfactory operation, the difference in fluid flow rates through the manifold conduit at spray and purge, respectively, should be substantial. For example, liquid spray apparatus constructed according to FIGS. 1-3, having 30 nozzles on a 2½ inch I.D. manifold with a 2 inch I.D. outlet valve, discharged about 70 g.p.m. during spray at about 40 p.s.i. inlet pressure. During purge the inlet pressure dropped to about 15 p.s.i., about 170 g.p.m. was discharged from the nozzles and about 120 to 140 g.p.m. through the outlet valve. The nozzle bodies were about 3 inches long and had inlet and outlet slots facing as in FIG. 1. All valve members of the nozzle bodies shifted satisfactorily as required for spray and purge simply by opening and closing the outlet valve.

The apparatus of FIGS. 1-3 produces what is known as a "fan spray" which is desirable for many uses. The nozzle bodies and valve members may however be designed to produce other types of spray, such as a hollow cone spray for which the modified nozzle body and valve member of FIG. 4 is adapted, this modification also showing a different location for the outlet port.

Referring to FIG. 4, the nozzle body 50 thereof has an externally threaded shank 52 which is received in correspondingly internally threaded opening 54 in single conduit manifold 10'. Body 50 has a chamber 56 formed therein by a bore of generally circular cross-section extending longitudinally entirely through the body from its end 58 within manifold 10' to its end 60 outside the manifold. Chamber 56 tapers toward its longitudinal axis at 62 to form a first shoulder and so

tapers again at 64 to form a second shoulder, which extends to spray discharge port 66 of substantially reduced diameter as compared with the diameter of the outlet port opening 68 in the end 58. An inlet port 70 is provided into chamber 56 through the wall portion of nozzle body 50 facing the inlet to the manifold.

The valve member 72 has an enlarged base 74 formed as a disc which is located outside the end 58 of the nozzle body and is of slightly larger diameter than port 68 to substantially close that port when the valve member is in the spray position shown in FIG. 4. The shank of valve member 72 has an annular enlargement 76 forming a stop shoulder which engages a lug 78 on the inner wall of chamber 56 when the valve member moves to purge position. Member 72 also has an enlarged head 80 which tapers toward its longitudinal axis at 82. Head 80 is provided with one or more, preferably at least two, angularly directed or helical external grooves 84 which extend to the end of the tapered portion 82. Tapered portion 82 is arranged to seat against shoulder 62 of the nozzle body for part of their respective lengths at their relative positions of FIG. 4, so that the sides of the groove or grooves 84 and shoulder 62 form open-ended tubular channels between the portions of chamber 56 at opposite sides of shoulder 62. A pin 86 extends from the end of head 80 and, in the position of parts shown in FIG. 4, extends centrally into spray discharge opening 66.

At the spray position of the parts shown in FIG. 4, fluid entering port 70 into chamber 56 flows over head 80 and through the groove or grooves 84 into the portion of chamber 56 beyond shoulder 62. The groove angularity causes the fluid to spiral about pin 86 over shoulder 64 and out spray discharge opening 66 as a hollow cone spray. As in the case of the FIGS. 1-3 embodiment, the slow flow with closed outlet valve to the manifold produces similar pressure conditions at inlet port 70 and outlet port 68 so that the fluid flow through the nozzle body to the spray outlet creates a pressure differential in the direction to hold the valve member in spray position with disc 74 seated against the end 58 of the nozzle body.

For purge, opening the outlet valve in manifold 10' (which may be the same as valve 16 of FIG. 1) causes relatively fast fluid flow in the manifold having a venturi effect on disc 74 producing a lower pressure than on inlet 70, which forces valve member 72 in the direction to unseat disc 74 from nozzle body end 58 until shoulder 76 engages lug 78. This moves head 80 away from shoulder 62 so that flow of fluid between head 80, shoulder 82 and shoulder 62 can clean out any debris that may have accumulated in groove or grooves 84 and flush it out the outlet 66 now enlarged by withdrawal of pin 86 inwardly therefrom, together with debris that may have accumulated in chamber 56 at opposite sides of shoulder 82. On again closing the outlet valve, the return to slow flow in the manifold reverses the pressure differential acting on the valve member which restores the valve member to the spray position shown in FIG. 4. If any large debris has caught in outlet 66 it will be pushed out by pin 86 moving back into the outlet.

It will be noted that in the FIG. 4 embodiment there are actually two outlets which are restricted in spray position and enlarged in purge position, the first one of these being formed by outlet 66 and pin 86 and the second one being formed by head 80, shoulder 82, groove

or grooves 84 and shoulder 62. While the use of pin 86 is desirable, it is not essential. If it is not used, outlet 66 has the same capacity during spray and purge so that the second outlet becomes the only one providing the necessary differential flow capacity at spray and purge. 5

I claim:

1. Shower apparatus comprising a conduit having an inlet adapted for connection to a source of fluid under pressure and having a main outlet, said conduit defining a single passage for the flow of fluid from said inlet to said outlet, valve means for controlling fluid flow from said outlet, a plurality of spray nozzles having body portions exposed to the flow of fluid in said passage, said body portions having inlet and outlet ports, said nozzles having a spray outlet for discharging fluid to the exterior of said conduit, said inlet port being disposed closer to said spray outlet than said outlet port and in the side of said body portions toward said inlet, said nozzles having a valve member movable therein between a spray position restricting the capacity of said spray outlet and a relatively non-restricting purge position, the capacities of said conduit, main outlet therefrom and spray outlets being such that fluid flow from said conduit main outlet may be controlled by said valve means to alter fluid flow in said conduit between 25

relatively slow and relatively fast, said inlet and outlet ports being so located in said nozzle bodies that said slow and fast flow rates produce respectively opposite pressure differentials in the fluid in the nozzle bodies to move the valve members thereof respectively to spray position and purge position.

2. Shower apparatus according to claim 1 wherein said outlet port is in the opposite side of the nozzle body from said inlet port.

3. Shower apparatus according to claim 1 wherein said outlet port is in the end of the nozzle body.

4. Shower apparatus according to claim 1 wherein said valve member has a tubular body portion with inlet and outlet openings and fluid flow to said spray outlet 15 while said valve member is in spray position is through said tubular body portion of said member from said inlet to said outlet openings.

5. Shower apparatus according to claim 1 wherein said valve member has an externally grooved body portion and said nozzle body has a shoulder engageable with said grooved portion while said valve member is in spray position so that fluid flow to said spray outlet is confined to flow through the groove or grooves thereof.
